UNITED STATES PATENT OFFICE.

THOMAS C. WHITEHEAD, OF DETROIT, MICHIGAN.

SHOE-BLACKING STAND.

Application filed February 9, 1925. Serial No. 3,049.

This invention relates generally to shoe-blacking stands and refers more particularly to portable stands having means for supporting a shoe while it is being cleaned.

- 5 One of the essential objects of the invention is to provide a stand of this type having an open top box that is adapted to receive the articles used for cleaning and polishing shoes and that is normally closed by 10 a cover formed of pivotally connected sections which may be moved to extended position, preferably at one end of the box, for supporting a shoe while it is being cleaned or polished.
- 15 Another object is to provide the cover with a relatively narrow section which will afford a sufficient bearing for a shoe but will not interfere with the movements of the hands while the shoe is being cleaned or 20 polished, for instance with a brush or strip of cloth.

25 A further object is to provide a neat and compact stand in which provision is preferably made for holding a plurality of addressed envelopes containing suitable coin cards which preferably have a list thereon of the parts and articles forming the complete outfit and which may be readily filled out and sent to the manufacturer or sales 30 office to obtain any article needed to maintain a complete outfit.

35 Still another object is to provide a strong and durable stand that is simple in construction and can be manufactured at a comparatively low cost.

With the above and other objects in view, the invention consists of certain novel features of construction, combinations and arrangements of parts as will be more fully 40 described, and particularly pointed out in the appended claims.

In the accompanying drawings:

- Figure 1 is a top plan view of a stand embodying my invention;
- 45 Figure 2 is an end view thereof;
- Figure 3 is a view of the stand with the cover thereof in extended position;
- Figure 4 is a perspective view of the stand with the cover in closed position;
- 50 Figure 5 is a perspective view with the cover in extended position.

Figure 6 is a top plan view of a slightly modified form of construction;

Figure 7 is an end view of the construction shown in Figure 6;

Figure 8 is a side elevation of the construction shown in Figure 6.

Referring now to the drawings in which like characters of reference designate corresponding parts throughout the several views, the numeral 1 designates a stand embodying my invention having an open top box 2 that is preferably supported at the corners thereof upon suitable legs 3 and is divided by a partition 4 into compartments 5 and 6 respectively for receiving suitable articles such as a dauber 7, brush 8, and tubes 9 of clean cream which may be used to clean and polish shoes and the like. As shown the compartment 6 is preferably 70 larger than the compartment 5 and is adapted to contain the brush 8, dauber 7 and one of the tubes 9 of clean cream, while the other compartment 5 is preferably provided with a hinged cover 10 and is adapted to receive 75 the extra tube 9 of clean cream as well as a plurality of envelopes 11 containing coin cards which preferably have a list thereon of the parts and articles forming the complete outfit and which may be readily filled 80 out and sent in the envelopes 11 to the manufacturer or sales office to obtain any of the articles needed to maintain a complete outfit.

In practice these coin cards are preferably filled out before the parts needed are used up or are completely worn out so that replacements may be made in due time. Thus a very convenient means is provided for maintaining a complete outfit. Any suitable means such as the spring clips 12 90 may be used to hold the dauber 7, brush 8, tubes 9 and envelopes 11 in proper position within the box 2.

In order that means may be employed alternately for closing the box and for supporting shoes and the like while being cleaned, I preferably provide the box 2 with a suitable cover 13 that is preferably formed of three sections 14, 15, and 16 which normally extend longitudinally of the box and 100 are preferably pivotally connected together at one end by a suitable pin 17 extending

transversely thereof. In order that these sections may be moved to extended position at one end of the box 2 for supporting a shoe while it is being cleaned, the intermediate section 15 is preferably pivotally connected at its other end to a suitable hinged bracket 18 anchored upon the adjacent end wall 19 of the box and the free ends of the outer sections 14 and 16 respectively are preferably held properly spaced apart by a cross bar 20. As shown, the bracket 18 is preferably constructed of sheet iron and is substantially U-shaped in form. The base 21 thereof is preferably countersunk in the upper edge of the end wall 19 of the box and is secured thereto by suitable screws 22 while the upstanding arms 23 are provided with aligned openings that receive a short pin 24 extending transversely of the intermediate section 15. Thus, with this construction, the cover 13 may be swung upwardly and outwardly about the pin 24 to the position shown in Figure 2 of the drawings, whereupon a shoe (not shown) may be placed upon the intermediate section 15 to be cleaned and polished. Any suitable means, such as the slotted adjusting rod 25 may be employed for bracing and reinforcing the sections 14, 15 and 16 respectively of the cover when disposed in the opened or extended position shown in Figure 2 of the drawings. If desired the mark of a shoe may be placed upon the intermediate section 15 of the cover to designate the proper location of the shoe while being cleaned and polished. As shown in Figure 1 of the drawings, the intermediate section 15 is preferably of such a width that it will afford a sufficient bearing for a shoe but will not interfere with the movement of the hands while the shoe is being cleaned and polished, for instance, with a brush or strip of cloth.

In order that the cracks between the sections of the cover 13 will not be noticeable when the cover is in closed position, I preferably provide a suitable finish piece 26 that is preferably secured to the outer sections 15 and 16 respectively. Inasmuch as this finish piece is secured to the outer sections only of the cover it will be readily apparent that it will not interfere in any way with the movement of the cover sections when moved to open or closed positions.

In Figures 6 to 8 inclusive, I have shown a slight modification in which the box 30 of the stand is divided by a partition 31 that is preferably located adjacent to one end thereof so as to provide a relatively large compartment 32 and a relatively small compartment 33. With this construction, the cover 34 is formed of one piece and is preferably hinged at one end thereof to an end wall 35 of the box. While supporting a shoe while being cleaned and polished, I preferably provide a narrow board 36 that

is adapted to slide longitudinally of the box and is preferably secured at its outer end to a suitable leg member 37. The normal position of the board 36 and the leg member 37 is shown by full lines and the extended position thereof is shown by dotted lines in Figure 6 of the drawings. For limiting the outward sliding movement of the board 36 there is a short pin 38 that projects downwardly from the board 36 adjacent to its inner end and is engageable with the inner face of the partition 31.

While it is believed that from the foregoing description the nature and advantages of the invention will be readily apparent, I desire to have it understood that I do not limit myself to what is herein shown and described, and that such changes may be resorted to when desired as fall within the scope of what is claimed.

Having thus described my invention, what I claim is:

1. In a shoe-blacking stand, the combination with an open top box in which articles for cleaning shoes may be kept, of a cover for the box having a portion movable outwardly beyond a wall thereof for supporting a shoe while being cleaned, said portion being substantially equal in width to the width of a shoe.

2. In a shoe-blacking stand, the combination with an open top box, of a sectional cover normally closing the box having one section movable horizontally beyond a wall of the box for supporting a shoe.

3. In a shoe-blacking stand, the combination with an open top box, of a sectional cover normally closing the box and having a section upon which a shoe may rest when said cover is moved to open position and having another section for supporting the section aforesaid.

4. In a shoe-blacking stand, the combination with an open top box, of a sectional cover normally closing the box, one section being pivoted to a wall of the box, and another section pivoted to said first mentioned pivoted section for supporting a shoe beyond the wall aforesaid of the box.

5. In a shoe-blacking stand, the combination with an open top box, of a sectional cover normally closing the box, one section being pivoted to a wall of the box, and a finish piece secured to certain of said sections concealing the cracks therebetween when said cover is disposed in closed position.

6. In a shoe-blacking stand, the combination with an open top box, of a cover therefor having pivotally connected sections, one of said sections being pivoted to a portion of the box.

7. In a shoe-blacking stand, the combination with an open top box, of a cover therefor formed of a plurality of sections, means

pivots connecting said sections together at one end thereof, and means for pivotally connecting one of said sections to a portion of the box.

8. In a shoe-blacking stand, the combination with an open top box, of a cover therefor formed of a plurality of sections, a pin

pivots connecting said sections together, means for pivotally connecting the intermediate section to a portion of the box, and means for holding the free ends of the outer sections properly spaced apart.

In testimony whereof I affix my signature.
THOMAS C. WHITEHEAD.
